US0D1113138S

(12) **United States Design Patent** (10) **Patent No.:** **US D1,113,138 S**
(45) **Date of Patent:** **** Feb. 17, 2026**

(54) **CASE FOR MOUTH GUARD**

(71) Applicant: **Shenzhen Shenlongke Technology Co., LTD**, Shenzhen (CN)

(72) Inventor: **Gang Jiang**, Shenzhen (CN)

(73) Assignee: **Shenzhen Shenlongke Technology Co., Ltd.**, Guangdong (CN)

(**) Term: **15 Years**

(21) Appl. No.: **29/974,686**

(22) Filed: **Nov. 25, 2024**

(30) **Foreign Application Priority Data**

Jul. 3, 2024 (CN) 202430414583.7

(51) **LOC (15) Cl.** **03-01**

(52) **U.S. Cl.**

USPC **D3/201**; D3/203.1; D3/215

(58) **Field of Classification Search**

USPC D3/201, 203.1, 205, 215, 273, 294; D9/420; D24/176

CPC A61C 7/08; A61C 19/02; A61C 8/0087; A45C 5/005; A45C 5/08; A45C 2011/007; A45C 11/008

See application file for complete search history.

(57) **CLAIM**

The ornamental design for a case for mouth guard, as shown and described.

DESCRIPTION

FIG. 1 is a front, left side perspective view of a case for mouth guard showing my new design;

FIG. 2 is a rear, right side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines in the drawings depict portions of the case for mouth guard and form no part of the claimed design.

1 Claim, 8 Drawing Sheets
